UNITED STATES PATENT OFFICE

FRANK J. CREQUE, OF CUYAHOGA FALLS, OHIO.

TOY BALLOON.

1,070,422.

Specification of Letters Patent. Patented Aug. 19, 1913.

Application filed June 10, 1912. Serial No. 702,849.

To all whom it may concern:

Be it known that I, FRANK J. CREQUE, a citizen of the United States of America, residing at Cuyahoga Falls, in the county of 5 Summit and State of Ohio, have invented certain new and useful Improvements in Toy Balloons, of which the following is a specification.

This invention relates to certain new and 10 useful improvements in toy balloons, the object being to provide novel means for maintaining the inflatable bag in an inflated condition, whereby the use of gas is dispensed with and air can be used for inflating the 15 balloons.

A still further object of the invention is to provide the balloon, which is so constructed that after the same has been inflated, means is provided for automatically closing 20 the valve and maintaining the same in closed position as long as the bag is inflated.

By the above construction, a balloon formed in this manner, can be collapsed and packed in a small package, and the purchaser can inflate the same as desired.

A still further object of the invention is to provide a novel form of holder for the balloon which is provided with a retaining ring forming a seat for the bag which also 30 forms means for holding the bag away from the valve-fastening member, whereby the inflation of the bag will hold the valve in a closed position under tension.

Other and further objects and advantages 35 of the invention will be hereinafter set forth and the novel features thereof defined by the appended claims.

In the drawings Figure 1, is a side elevation of my improved construction of balloon, showing the application of the same 40 to a staff for supporting the same; Fig. 2, is a detail vertical section through the neck of the balloon showing the valve construction; Fig. 3, is a perspective view of the 45 balloon retaining member; Fig. 4, is a side elevation of a pair of balloons arranged in position upon the holder, a staff of which is provided with a handle portion in order to form a dumb-bell; and Fig. 5, is a section 50 taken on the line 6—6 of Fig. 4.

In carrying out my improved invention, I employ an inflatable bag 1 which is preferably formed of rubber having an extension 2 to form a neck, in which is arranged a 55 tubular member 3 which is secured therein by forming the end of the neck with a re-

taining ring 5 which is adapted to hold the tubular member 3 securely in position within the neck and said tubular member is preferably formed conical, and is of a yielding material, such as cork; the bore thereof being provided with a conical valve seat 6 at its inner end in which is adapted to be seated a conical valve 7, carried by a valve-stem 8 which is provided with a hook 9 at its opposite end, for the purpose later described.

The inward movement of the valve 7 is limited by the hook 9 and it will be seen that when forced into the position as shown by dotted lines in Fig. 2, the inflatable bag 70 can be inflated by forcing air through the member 5 and by drawing outwardly on the valve-stem the conical valve will be drawn into its seat at the same time the yielding tubular member yielding to such an extent 75 that the bore thereof will be closed so as to form an air-tight joint to retain the bag in an inflated condition. The pressure of the air against the valve holds the same firmly in its seat.

In order to provide means for retaining the valve in a closed position under tension, and to provide means for supporting the balloons, I provide a ring-shaped holder 10 which is preferably formed of wire having 85 an extension 11 terminating in a loop portion 12, which is in longitudinal alinement with the central portion of the ring and over which is adapted to be hooked, the hook 9 of the valve-stem 8, after the balloon has been placed in position within the ring so that the valve will be held in a closed position under tension by the flexible bag, the distance between the loop portion 12 and the ring 10 being determined previously and 90 according to what size of bag is to be used. It will be seen that the inflated bag pressing against the ring portion of the holder forms means for holding the valve in its seat in such a manner that all danger of the valve 95 being accidentally unseated is prevented as long as the bag is inflated. By the expansion of the bag working against the ring, it forces the bag upwardly so as to apply tension to the valve stem. The loop portion 100 12 is provided with a staff 13 which is preferably formed of a single piece of wire terminating in a ring portion 15 forming a handle by means of which the staff can be supported in the ordinary manner.

In Fig. 4, I show the application of my invention to a dumb-bell, which comprise

a longitudinally slotted handle 16 in which is secured a staff 17, which is provided with a bag holder at each end, constructed in the same manner as that previously described, 5 and by this construction, a pair of balloons can be supported in order to obtain a dumb-bell effect.

From the foregoing description, it will be seen that I have provided an inflatable bag 10 with a valve which is held in closed position by the inflation of the bag when arranged within the holder, and by the aid of the pressure of air within the bag, and by this construction, the valve can be unseated by 15 simply removing the bag from the holder and forcing inwardly on the valve.

I claim:

1. An inflatable bag provided with a valve-controlled inlet, and a holder for said bag having a connection with the valve of 20 said bag for retaining said valve in closed position by the expansion of said bag.

2. A toy balloon comprising an inflatable bag having a valve-controlled inlet, a holder 25 for said bag, and a connection from said valve to said holder for holding said valve in closed position by the expansion of said bag.

3. In a toy balloon, the combination with 30 a holder comprising a ring-shaped frame and a spaced loop in alinement with said frame, of an inflatable bag having a neck arranged within said ring portion, a reciprocating valve for closing said neck, and a 35 connection from said valve to said loop portion.

4. A toy balloon comprising a ring-shaped holder having a spaced loop portion in alinement therewith, an inflatable bag provided 40 with a neck arranged within the ring portion of said holder, a tubular member arranged within the neck of said bag provided with a valve seat, and a valve working in said member having a connection with said 45 loop portion.

5. In a toy balloon, the combination with 50 an inflatable bag having a valve-controlled inlet opening, of a holder comprising a ring portion and a loop portion in alinement with the center of the ring portion, and a connect- 55 necting said valve to said loop portion.

6. A toy balloon comprising an inflatable bag having a valve-controlled inlet, a holder for said bag comprising a ring portion and a loop portion spaced apart, said ring portion forming a seat for the bag, and a connection from said valve to said loop portion. 55

7. A toy balloon, comprising an inflatable bag provided with a neck portion terminating in a ring, a tubular member secured 60 within said neck portion by said ring provided with a valve seat at its inner end, a valve stem working through said tubular member having a valve at its inner end, and a holder for said bag comprising a ring portion forming a seat for the bag and a loop portion to which said valve stem is connected for maintaining said valve in a closed position by the expansion of said bag. 65

8. A toy balloon comprising a holder having 70 a ring portion and a loop portion spaced apart, an inflatable bag seated upon said ring portion, said bag being provided with a valve-controlled inlet opening, and a connection from said valve to the loop portion. 75

9. A toy balloon comprising an inflatable bag, a valve for closing the opening of said bag, a holder for said bag having a connection with said valve for maintaining the 80 valve in closed position by the expansion of said bag.

10. As a new article of manufacture, a toy balloon comprising an inflatable bag provided with a neck portion, a tubular member arranged within said neck portion 85 formed of yieldable material and provided with a valve-seat, a co-acting valve, and a holder for said balloon comprising a ring portion and a loop portion, and a connection from said valve to said loop portion. 90

11. A toy balloon comprising an inflatable bag having an inlet, a valve for closing said inlet, a support for said bag, and a connection from said support to said valve for maintaining the valve in closed position by 95 the expansion of said bag.

In testimony whereof I affix my signature in presence of two witnesses.

FRANK J. CREQUE.
